FUEL BURNER CONTROL SYSTEM

Filed March 1, 1939

UNITED STATES PATENT OFFICE

2,232,385

FUEL BURNER CONTROL SYSTEM

Edward J. Haedike, Chicago, Ill., assignor to National Machine Works, Chicago, Ill., a corporation of Illinois

Application March 1, 1939, Serial No. 259,191

3 Claims. (CL. 158—28)

The invention relates to fuel burner control systems and more particularly to control systems for fuel burners provided with auxiliary or pilot burners of the on-off type. It will be understood that so-called on-off pilot burners do not burn continuously, but are lighted only when used for igniting the main burner and are usually maintained lighted during the operation of the main burner. During the intervals in which 5 the main burner is off the pilot burner is also off. Obviously, a saving in fuel is accomplished when using such an on-off pilot burner as distinguished from a pilot burner which is maintained in operation at all times, irrespective of 10 the operation of the main burner. Furthermore, with the control system herein disclosed, there is an obviation of a hazard sometimes occurring with constantly burning pilots. In particular, the supposedly constantly burning pilot may go 15 out and danger then arises when fuel is supplied to the main burner. With an on-off pilot, however, the ignition cycle for the pilot is repeated before fuel is supplied to the main burner so that there is positive insurance of a pilot 20 flame to light the main burner when the latter is turned on.

One object of the present invention is to provide a new and improved control system for a fuel burner with an on-off type of pilot burner, 30 in which the supply of fuel to the main burner cannot, under any circumstances be reinitiated after the pilot burner has been shut off, except after a complete repetition of a predetermined pilot ignition cycle.

35 A further object of the invention is to provide an electrical control system for a fuel burner with an on-off type of pilot burner, which system is of such character as to insure positively a sequential operation of the ignition mechanism 40 for the pilot burner and the fuel supply means for the main burner.

Another object of the invention is to provide 45 in a control system for a fuel burner with an on-off type of pilot burner, a novel system of interlocks for positively insuring proper conditioning of the main burner before ignition of the pilot burner and for also preventing the supply of fuel to the main burner until the pilot burner has been ignited.

50 Still another object of the invention is to provide an electrical control system for a fuel burner with an on-off pilot burner, all operable under the general control of a main thermostat provided with a heat-anticipation heater and in 55 which said heater is governed by an improved

and simplified circuit interconnected with the controls of the main and pilot burners.

Further objects and advantages of the invention will become apparent as the following description proceeds, taken in connection with the 5 accompanying drawing in which:

Figure 1 is a wiring diagram and diagrammatic layout of a fuel burner control system embodying the present invention.

Figs. 2 and 3 are wiring diagrams similar to 10 Fig. 1 of two modified forms of control systems embodying the invention.

For purposes of illustration and explanation of its various novel features, the invention has been exemplified herein (Fig. 1) in a control system 15 suitable for a main gas burner (not shown) supplied with fuel through a main gas line 10. It will be appreciated that the invention is also applicable to control systems for other types of fuel burners.

In brief, the combustion mechanism includes, 20 in addition to the main burner, a pilot burner 11 and a blower (not shown), driven by an electric motor 12, for supplying air for combustion at the burners. Gas is supplied to the pilot 25 burner 11 through a branch conduit 13 on the main supply conduit 10. Separate shut-off valves 14 and 15 serve, respectively, to control the flow of fuel to the main and pilot burners, 30 these valves being actuated in a manner which will hereinafter appear. The general control of the system is accomplished by means of a main thermostat 16, which may be of the conventional bimetallic double-contact type as shown, or of 35 any other suitable form. The term "main thermostat" as used herein designates a thermostat or similar thermal responsive device actuated in accordance with the temperature of the air or other medium in a space, such as a room, which is heated either directly or indirectly from the 40 main burner.

Generally stated, the associated control system is adapted, under normal conditions, to operate 45 the combustion apparatus in the following cycle. When the main thermostat 16 calls for heat, fuel is supplied to the pilot burner 11 and an ignition device is set in operation to ignite the fuel at the pilot burner. Preferably, the fuel supply means for the pilot burner is interlocked with the blower motor 12 so that fuel will not be supplied to the 50 pilot burner until both the main and pilot burners are conditioned for proper combustion by having the blower operating at or above a predetermined minimum speed. In response to a 55 successful ignition of the pilot burner 11 the 55

valve 14 is opened so as to supply fuel to the main burner. This supply of fuel to the main burner continues until the temperature at the main thermostat 16 is raised to a predetermined point at which time both the main and pilot burners are again shut down. Preferably a heat-anticipation heater is associated with the main thermostat, as will hereinafter appear, to accelerate its point of opening. This cycle is 10 repeated intermittently with such frequency as may be required to maintain the main thermostat within a predetermined temperature range.

Before proceeding with a description of the interrelation of the control system elements, the 15 various parts will be identified. In the particular arrangement shown in Fig. 1, the control apparatus includes a pilot ignition device, shown as an electrical resistance heater coil 17, which in the actual construction is located closely adjacent the pilot burner 11. To interlock the pilot burner supply valve 15 with the blower motor 12, a valve of the centrifugal type is used and is mechanically coupled with the blower motor 12 so that the valve 15 will be open only when the 20 motor 12 is operating at or above a predetermined minimum speed. Also associated with the pilot burner 11 is a thermally actuated flame detector shown as a thermocouple 18, connected in circuit with an energizing winding 19 of an associated relay designated generally by the numeral 20. This relay is provided with a pair of normally open contacts 21, which are closed upon energization of the actuating winding 19.

As to the main burner shut-off valve 14, an actuating solenoid 22 is provided for this valve. When energized, the solenoid 22 serves to open the valve 14, this valve being normally biased to closed position. Current for actuating both the pilot ignition coil 17, and valve actuator solenoid 22, is supplied under the control of a main relay 23, as well as a two-position switching device designated generally by the numeral 24. The interconnection of this relay and switching device with the thermally controlled relay 20 will 40 hereinafter appear. The main relay 23 embodies an actuating winding 25, as well as normally open high and low voltage contacts 26 and 27, respectively. Similarly, the switching device 24 has been shown as being a double-pole double-throw 45 relay embodying an actuating winding 28 as well as two sets of double-throw contacts 29 and 30 with cooperating fixed contacts 29^a—29^b and 30^a—30^b, respectively. The contacts 29^a and 30^a are normally closed; that is, when the actuating winding 28 is deenergized.

Current for the system may be supplied, for example, from suitable alternating current supply line L₁ and L₂, which may be of a comparatively high voltage such as 110 volts. Across 60 these supply lines is connected a primary winding 31 of a step-down transformer 32. From a secondary winding 33 of this transformer, low voltage alternating current is supplied to lines L₃—L₄ for the low voltage portions of the control circuit. In connection with the current supply arrangement, it should also be noted that the system preferably includes a step-down transformer 34 having a primary winding 35 and a secondary winding 36. As will hereinafter appear in greater detail, this transformer serves to supply current alternatively to the pilot ignition coil 17 or to the main burner valve actuating solenoid 22.

Initiation of the normal cycle of operation is 75 accomplished by closure of contacts 37 and 38

on the main thermostat 16. As the ambient temperature at this thermostat falls to a selected minimum value, the thermostat blade warps (to the left as shown in Fig. 1) and closes both the contacts 37 and 38. The lower contact 38 actually closes first but this sequential type of closure, for the moment, has no effect upon the system. Closure of the two contacts 37 and 38 energizes the main relay actuating winding 25 (through a circuit L₃—25—39—29—29—37—10 16—38—40—L₄). It will be understood that the primary winding 31 of the main transformer 32 is connected across the high voltage supply lines L₁—L₂ at all times so that the secondary winding 33 of this transformer is also energized at all 15 times to provide a suitable low voltage across the supply lines L₃—L₄.

Actuation of the main relay 23 causes it to close its two sets of contacts 26 and 27. Closure of the contacts 27 completes an alternative energizing circuit for the main relay winding 25, through a heat-anticipation heater coil 41 associated with the main thermostat 16, but little or no current flows through this coil for the moment since it is in shunt with the lower resistance energizing circuit for the relay winding which was set forth above. Closure of the other set of main relay contacts 26, however, connects the blower motor 12 across the high voltage supply lines L₁—L₂, thereby setting it in operation. 30 Furthermore, closure of these contacts 26 also connects the primary winding 35 of the transformer 34 across the supply lines L₁—L₂. As a consequence, current is supplied from the secondary winding 36 of this transformer, through 35 contacts 30—30^a of the relay 24 to the ignition coil 17.

From the foregoing, it will be seen that the first step in the cycle, namely, lighting of the pilot burner 11, is initiated in response to energization 40 of the main relay 23 by closure of the main thermostat contacts 37—38. To summarize, the energization of the main relay 23 causes current to be supplied to the pilot burner ignition coil 17 as described above. Furthermore, the main 45 blower motor 12 is also started as described and when it actually reaches its proper operating speed the centrifugally actuated valve 15 is opened so as to permit gas to flow through the supply conduit 13 to the pilot burner 11.

The second step in the cycle of operation, namely, the supply of fuel to the main burner, by opening of the associated valve 14, is initiated 50 in response to a successful ignition of the pilot burner 11. When the flame at the pilot burner 11 is burning properly, it heats the thermocouple 18 so that the associated relay 20 closes its contacts 21. Closure of these contacts serves to energize the actuating winding 28 of the double-pole, double-throw relay 24 (through a circuit L₃—28—42—21—40—L₄). Energization of this latter relay, or switching device, serves to shift both of its double-throw contacts 29 and 30 to their upper positions (as viewed in Fig. 1) so that contacts 29—29^b and 30—30^b are closed. 60

Closure of the contacts 29—29^b interrupts the previous energizing circuit for the main relay winding 25 and completes an alternative one through the relay's own contacts 27. Shifting of the main relay energization to a non-pick-up 70 or holding circuit is done for a purpose which will hereinafter appear. Closure of the other set of contacts 30—30^b serves to energize the main burner valve solenoid 22 and to interrupt the energizing circuit for the pilot ignition coil 75

11. It should be noted at this point that the solenoid 22 and ignition coil 17 are both energized from the transformer 34 and under the control of the double-throw contact 30 so that a sequential energization of these two devices is positively insured. Furthermore, simultaneous energization of the devices, due to improper operation of any of the control parts, is absolutely precluded by virtue of the particular switching arrangement used. When the solenoid 22 is energized in this manner it opens the associated valve 14 so that fuel is supplied to the main burner and this fuel is, of course, ignited by the pilot burner 11.
15. To prevent so-called "overshooting" of the heat supply for the space in which the main thermostat 16 is located, the heat anticipation heater coil 41 is located closely adjacent this main thermostat. When the medium surrounding the main thermostat 16 has increased in temperature a predetermined amount, the thermostat blade is warped (to the right as viewed in Fig. 1) so that the contacts 31 open, although the contacts 38 still remain closed at this point. Opening of the contacts 31, interrupts the shunt previously formed about the heater coil 41 so that the energizing current for the main relay actuating winding thereupon flows through the heater coil 41. The heat radiated from this coil warms the main thermostat 16 so that it warps still further and opens its other contacts 33, hereby finally interrupting the energizing circuit for the main relay winding 25. Thereupon the main relay contacts 26 and 27 drop out with the result that the blower motor 12 is deenergized, as is the transformer 34 which theretofore supplied current to the main burner valve actuating solenoid 22. When the solenoid 22 is deenergized the main burner valve 14, of course, closes, and similarly the pilot burner valve 15 is closed upon stoppage of the blower motor 12. In this way both the main and pilot burners are shut down and remain so until the main thermostat 16 again calls for heat. When the thermocouple 18 cools, the relay 20 opens, thereby deenergizing the double-pole double-throw relay 24 and restoring the system to its initial condition preparatory to re-cycling.
50. Dangerous partial recycling of the system is prevented by the novel arrangement herein disclosed. In other words, the system has been so devised that if the cycle is interrupted at any time, the supply of fuel to the main burner can only be reinitiated after a complete repetition of the pilot ignition cycle during one of the complete normal cycles for the whole system such as that previously described. It will be understood that such interruptions in a cycle are likely to occur for various reasons. For one thing, the voltage on the main supply lines L₁—L₂ may fall momentarily. For another thing, it is often desirable to include a pressure responsive device or the like in a boiler associated with the main burner so that if the pressure in the boiler becomes excessive the main burner will be shut down irrespective of the temperature of the main thermostat. For this latter purpose, a pressure responsive device 43 may be provided to open a pair of normally closed contacts 44 whenever the boiler pressure reaches a predetermined maximum value. These contacts 44 are connected in series with the main thermostat contacts 38 so that opening of the contacts 44 deenergizes the main relay 23 and, therefore, shuts down the system just as in the case of the opening of the main thermostat contacts 38 as previously described. The danger in such instances arises from the fact that the contacts 44 may be again closed by a quick drop in pressure in the boiler before the thermocouple 18 has cooled off. Similarly, the voltage may be restored to the supply lines L₁—L₂ before the thermocouple has cooled. In such case, if the main relay 23 could immediately pick up again, the thermocouple controlled relay 20 would be closed and as a result contacts 30—30^a closed so that the main burner valve 14 would be opened by the solenoid 22 at once and without any reignition of the pilot burner 11. Any such initiation of the cycle at an intermediate point is, however, positively precluded by the arrangement herein disclosed.

connected in series with a thermocouple 18, associated with the pilot burner 11. By using such a switch, the intermediate relay 20 is eliminated. Otherwise the circuit is substantially identical 5 in form and operation with that of Fig. 1, and the same reference numerals have been used to identify corresponding parts.

Although certain particular embodiments of the invention have been shown and described in 10 some detail there is no intention to thereby limit the invention to such embodiments, but, on the other hand, the appended claims are intended to cover all modifications and alternative constructions falling within the spirit and scope of the invention. 15

I claim as my invention:

1. In a control system for a main fuel burner having an on-off pilot burner, the combination of an electrically energizable ignition device for 20 the pilot burner; electrically operated fuel control devices for the main and pilot burners; means including a main relay for controlling an electric supply circuit from which the pilot burner control device is energized to admit fuel to the pilot 25 burner, said main relay having an initial energizing circuit and a separate non-pick-up holding circuit; a two-position switching mechanism operable in one position to complete a supply circuit from said first named supply circuit controlled by 30 said main relay, to said pilot ignition device and operable in the other position to complete a supply circuit from said first named supply circuit to said main burner fuel control device, said switching mechanism also being operable only in 35 said one position to complete said initial energizing circuit for said main relay and operable in said other position to interrupt said initial energizing circuit and to complete said relay holding circuit; and a main thermostat operable in 40 one position to condition said relay energizing circuit for completion by said switching mechanism and in its other position to interrupt said holding circuit, said switching mechanism being normally urged to said other position, and means 45 for actuating said switching mechanism to said one position in response to pilot ignition.

2. In a control system for a main fuel burner having an on-off pilot burner, the combination of a main thermostat provided with first and sec- 50 ond sets of contacts arranged to be opened se- quentially in the order named as the thermostat is heated, a heat-anticipation electric heater associated with said thermostat, electrically en- ergizable ignition and fuel supply control devices 55 for the pilot and main burners respectively, means including a main relay for controlling an elec- tric supply circuit from which the pilot burner

control device is energized to admit fuel to the pilot burner, said main relay having an initial en- 5 ergizing circuit controlled by both of said sets of contacts and a separate non-pick-up holding circuit, a two-position switch mechanism oper- able in one position to complete a supply circuit from said first named supply circuit to said pilot ignition device and operable in the other position to complete a supply circuit from said first named supply circuit to said main burner fuel 10 control device, said switching mechanism also being operable only in said one position to com- plete said initial energizing circuit for said main relay and operable in said other position to inter- rupt said initial energizing circuit and to complete 15 said holding circuit therefor, said holding circuit embodying two parallel connected branches with 20 said heater included in one branch and said first set of contacts included in the other branch, said switching mechanism being normally urged to said other position, and means for actuating said switching mechanism to said one position in response to pilot ignition.

3. In a control system for a main fuel burner having an on-off pilot burner, the combination of 25 a main thermostat provided with first and second sets of contacts arranged to be opened sequen- tially in the order named as the thermostat is heated, a heat-anticipation electric heater asso- 30 ciated with said thermostat, electrically energiz- able ignition and fuel control devices for the pilot and main burners respectively, a first switching means operable alternatively to connect said igni- 35 tion device and said main burner fuel control device to a source of current for actuation of the same, said first switching means being normally urged to a position for connecting said ignition device to said source of current, means operable in response to ignition of the pilot burner for 40 shifting said first switching means to its alternate position to connect said main fuel burner control device to said source of current, a second switch- 45 ing means operable when shifted from a first position to a second position to disable both said ignition and pilot burner fuel control devices, electromagnetic means for operating said second 50 switching means and operable when energized to retain said second switching means in said second position, and an energizing circuit for said elec- 55 tromagnetic means including a pair of parallel connected branches connected in series with a common portion of the circuit, said first set of thermostat contacts being interposed in said common portion, said second set of contacts in one of said parallel branches, and said electric heater in the other branch.

EDWARD J. HAEDIKE.
